DIGGING TOOTH FOR EXCAVATORS

William A. Nelson, Willoughby, Ohio, assignor to The Cleveland Trencher Company, Cleveland, Ohio, a corporation of Ohio

Application August 6, 1952, Serial No. 302,916

2 Claims. (Cl. 37—142)

This invention relates to improvements in or relating to digging or rooter teeth for use with the digging buckets of rotary excavator wheels, or excavating chains of trenching machines, and the like. More particularly, the present invention relates to improved excavator teeth having removable cutting or rooter members at their digging edges.

The digging or rooter teeth or excavating machine buckets are subjected to severe shock, usage and/or wear, particularly when the machine is operated in stony soil or in areas where heavy roots are encountered. In the past teeth have been provided which comprised a base adapted to be fastened to the excavating buckets by welding, bolts, rivets, or the like, and which carried removable tips. This has facilitated reforging the tip to restore it to its original shape; rehardening of the wearing surface of the tip; building up of the tip by welding or forging operations; or replacement by a new tip. Diverse constructions have been used to mount the tips on their bases. Generally such constructions included means such as bolts, keys or the like. The impacts to which the teeth are subjected during excavating operations soon distort such bolts etc., and prevent removal of the tips for replacement or sharpening.

Another method of mounting the tip on the base is shown in Patent No. 2,397,521 issued to my assignee, The Cleveland Trencher Company, April 2, 1946. This patent discloses a base and tip having telescoping portions, substantially rectangular in cross section and provided with tapered walls, and wherein such portions are formed to insure contact between the corners of the internal member with the walls of the coating socket, prior to engagement between the other surface of such coating portions. Such rooter teeth have been successfully used for some time. However in the last few years a considerable advance has been made in the metallurgy. This has resulted in the production of a higher grade of metals, especially with relation to their properties on the one hand and manufacture and treatment on the other. Such advance has permitted the provision of rooter teeth which are much harder and capable of use for a much longer period of time than the teeth formerly used. However these advances have increased the difficulty in attaching the removable tip to the rooter shank to insure a secure attachment and yet facilitate the removal of the tip when desired.

A more specific object of the present invention is to provide a rooter base and removable tip therefor which are so constructed as to overcome the disadvantages of structures used in the past and which will permit the use of the best materials obtainable for the manufacture of the base and tip, and thereby prolong the life of the base and tip.

The various objects and features of this invention will be more fully understood from the following detailed description of a typical form of the invention illustrated in the accompanying drawings, in which:

Fig. 1 is a fragmentary view of a portion of an excavating wheel illustrating an excavating bucket provided with the improved excavating teeth;

2

Fig. 2 is a plan view of the improved excavating tooth showing the tip in place on the tooth base;

Fig. 3 is a view similar to Fig. 2, but illustrating the tip separated from the base;

Fig. 4 is a central longitudinal section through the base and separated tip, the plane of the section being indicated by the lines 4—4 on Fig. 3;

Fig. 5 is a fragmentary longitudinal section similar to Fig. 4 but illustrating the start of the assembly of the base and tip;

Fig. 6 is a fragmentary central longitudinal section similar to Fig. 4 illustrating the base and tip completely assembled, the plane of the section being indicated by the lines 6—6 on Fig. 2;

Fig. 7 is a fragmentary section similar to Fig. 6 but taken in the plane indicated by the lines 7—7 on Fig. 3;

Fig. 8 is a fragmentary longitudinal section the plane of which is indicated by the lines 8—8 on Fig. 6;

Fig. 9 is a transverse section through the tooth base as indicated by the lines 9—9 on Fig. 3;

Fig. 10 is a transverse section through the tooth tip as indicated by the lines 10—10 on Fig. 3; and

Fig. 11 is a transverse section through the assembled base and tip, the plane of which is indicated by the lines 11—11 on Fig. 2.

Referring now to the drawings, particularly to Fig. 1, 15 indicates a portion of an excavating wheel provided with excavating buckets, one of which is indicated at 16. The machine itself may be of the type shown in Patent 30 No. 2,280,004, issued April 14, 1942, to my assignee, The Cleveland Trencher Company. Suitable mechanism, not shown, rotates the wheel in the direction of the arrow in Fig. 1, so that the forward edge of the excavating buckets will engage the material to be excavated.

The improved rooter or digger teeth 19 are shown as being applied to the bucket 16 by bolts or rivets 17 which pass through openings 18 in the tooth base 20, and through the wall of the bucket. Excavating tips 30 are shown in place on the teeth 19. As illustrated each tooth base 20 has a forwardly extending shank portion 21 which enters a socket 31 formed in the tooth tip or wearing member 30.

The socket 31 of the tip 30, and the shank 21 of the tooth base are substantially rectangular in transverse section, except for the undercut portions 26, and are so arranged and constructed that the tip is held in place on the shank solely by frictional engagement between the walls of the shank and socket. As illustrated in the drawings and particularly in Figs. 4 and 8 the walls 24, of the shank 21, and the walls 34 of the socket 31, are all tapered. The tapers of the shank is indicated by the angle A, and those of the socket by the angle B. The tapers of the shank 21 and of the socket 31 are formed concentric with the center lines of the corresponding parts. To hold the tip on the shank solely by frictional engagement the angles of tapers A of the shank are between five and nine degrees, and the angles of tapers B of the socket are from one-half to two degrees smaller than the corresponding angles of taper of the shank. Preferably the angles of taper A are identical, as are the angles of taper B.

I prefer to forge the shank and base of the tooth of a high grade steel alloy capable of being forged and hardened so as to withstand the digging action for relatively long periods of time. It has also been found preferable to set the tapers of the shank at eight degrees and the tapers of the socket at seven degrees.

The differences in the tapers between the socket and the shank permits the use of forgings without need for machining or finishing the coating surfaces of the tapers. The side walls of the shank are beveled or tapered from their longitudinal media lines inwardly and toward the

3

upper and lower surfaces of the shank, as shown in Figs. 9 and 11, while the side walls of the socket are substantially arcuate. The radius of the arcs of the side walls is such as to prevent binding contact between the central and major portions of the coating side walls and socket at all times. The width of the shank and socket are so related as to insure contact between all four corners of the shank and the walls of the socket prior to engagement of the top and bottom surfaces thereof. Thus the tip is held firmly against rocking movements on the shank. Further, this initial contact at the corners has another distinct advantage, namely, a small space or low pressure area exists between the faces of the shank and the faces of the walls of the socket, thus permitting swelling of the shank due to compression thereof caused by impact during the digging operation. The spaces between the central portion of the top and bottom walls of the shank are increased by undercut areas 26 of the shank, caused by repeated impacts during the digging operations. The swelling action of the shank reacts against the weaker or wider face of the tip, which, due to its width, may warp slightly to accommodate this swelling action.

With the exception of the undercut portions 26, the tooth so far described is substantially that of Patent 2,397,521, heretofore mentioned. Accordingly reference may be had to that patent for a more complete description of the details of such tooth base and shank, together with the manner in which they cooperate one with the other. Such a construction facilitates the use of detachable tips when the shank and tips are made of many types of metal alloys.

As heretofore mentioned, considerable difficulty has been encountered in maintaining the tip in position on the shank when using the higher grade metal alloys being produced at the present time and or improved hardening treatment for manufacture of the tip, particularly when the excavating wheel is inadvertently operated in reverse direction. To overcome these disadvantages and permit the use of the higher grade metal alloys thereby lengthening the life of the tip, the present invention provides additional means to retain the tip in place on the shank and yet permit it to be readily removed for purposes heretofore described.

Referring to the drawing it will be seen that the upper surface 40 of the shank 21 is provided with a raised boss or protuberance in the form of a button 41, this protuberance or button has conical side walls 42 and its upper surface extends about one sixty-fourth of an inch above the upper surface of the corners of the shank. The boss 41 is positioned near the end of the shank and intermediate its side walls. The upper surface of the boss is made parallel with the upper surface of the shank 21.

The height of the boss 41 is such that in assembly it will enter the tip socket 31 as shown in Fig. 5 and seat firmly in that position. After the tip has been positioned as shown in Fig. 5, it is fully seated by applying a driving impact to the end 44 of the tip, until it reaches substan-

tially the position of Fig. 6. In this position the engagement of the tapered walls of the shank 21 with the tapered walls of the tip socket by corner engagement, as heretofore described, prevents further movement of the tip onto the shank.

The increased holding power of the tooth of this invention comes as a result of an actual deformation of the upper flat wall 45 of the tip which is realized by the driving force applied when the tips are hammered onto the bases. This distortion also causes the binding action between the corner of the tip and in the corner of the shank to be increased. However, despite the increased holding power it has been found that the tip may be removed by hammering against the rear surfaces 46 of the tip. It has likewise been found that despite the deformation of the wall 45, the tip may be reapplied to the shank several times without materially affecting the holding power.

I claim:

1. A digging tooth for an excavator, said tooth comprising a metallic base member and a metallic tip member, said base being adapted to be attached to an excavator member and having a shank substantially rectangular in cross section throughout its length, at least one of the walls of the shank being tapered, a tooth tip adapted to be removably positioned on said shank, said tip having a socket substantially complementary in cross section that of the shank and having at least one of its walls being tapered, the tapered wall of said socket being planar, the tapered wall of said shank having an outward extending protuberance, said protuberance rising above the wall of the shank intermediate its sides and adapted to freely enter the socket when the tip is initially positioned on the shank and to thereafter distort the wall of the tip as the tip is driven onto the shank and to retain such wall distorted as long as the tip is in position on the shank, and wherein when the tip is in position on the shank said protuberance exerts a constant outward deforming pressure on the coating wall of the tip thereby drawing the associated corners of the tip into tighter engagement with the coating corners of the shank respectively.

2. A digging tooth according to claim 1 wherein said protuberance comprises a button shaped member arising above the wall of the shank and is spaced inward from the associated side walls of the shank and inward from the end of the shank.
